UNITED STATES PATENT OFFICE.

WILLIAM M. NEVOTTI, OF OMAHA, NEBRASKA.

ELECTRICAL HAIR WAVER.

Application filed October 22, 1926. Serial No. 143,381.

This invention relates to an electrical hair waver of such construction that it may be used by an individual in the treatment of his or her own hair, or may be used by hair dressers generally.

The principal object of this invention is to provide tines or prongs of bow shape of such construction and arrangement that they will elevate and dispose the hair in loops between two electrically heated pressure-bars to thereby expedite operation as well as producing waving and undulation of improved form and more attractive appearance than ordinary.

Other objects more specific will be explained hereinafter.

The invention is fully described herein and is illustrated in the accompanying drawings wherein;

20 Fig. 1 is a view of the device in longitudinal section showing the normal position of the bow-shaped tines or prongs.

Fig. 2 is a sectional detail showing the position of parts when the prongs have been 25 elevated.

Fig. 3 is a transverse section through the casing and parts on line 3—3 of Fig. 1.

Fig. 4 is a transverse section on line 4—4 of Fig. 1.

30 Fig. 5 is a transverse section on line 5—5 of Fig. 1.

Fig. 6 is an enlarged sectional detail to illustrate the mountings of a bow-shaped prong.

35 Fig. 7 is a broken away plan view to show the position of parts.

Fig. 8 is a plan view of the device, the casing being in section.

Fig. 9 is an end view of the device, and 40 Fig. 10 is a transverse section on line 10—10 of Fig. 1.

Referring now to the drawing for a more particular description, the hair waver consists in part of a pair of handles 11 which, 45 in the drawings, are shown broken away.

Numerals 12 and 13 indicate a pair of heated metallic pressure-bars, each being rigid with a handle, these parts being connected to permit parallel movements by means of a pivot 14 and lever bars.

50 The bar 12 is preferably semicircular in cross section and the bar 13 is circular in cross section, and it will be understood that the handles may be grasped in the hand of an

operator to cause the bars to move toward each other for pressing the hair therebetween.

These parts have been in general use for the treatment of hair and no claim of novelty is made for the use of heated bars.

These hollow bars may be electrically heated, and for this purpose I have shown electrical conductors A and B adapted to be energized by any suitable source of electrical supply, each hollow bar being provided with an electrical coil (not shown) for communicating heat to said bars.

The bars 12 and 13 may be pressed toward each other, subject to the resistance of a spring 15, said spring operating to normally cause said bars to remain in spaced relation as shown in Fig. 8 of the drawings.

In order that hair, during operation may be elevated to form the loops, as first mentioned, and this movement of the hair will be coincident with the movements, toward each other, of the pressure-bars, I provide certain parts to now be described.

Numeral 16 indicates a carrier-plate upon which are pivotally mounted, a plurality of bow-shaped prongs 17, said plate being adapted to be reciprocated longitudinally by means to be described.

Numeral 18 indicates a supporting plate which is disposed above the plate 16, and is 85 stationary with the casing 19, by means of a pair of hangers or arms 19' and 19" and at 20 are indicated a pair of links each having pivotal connections at the ends of the plates 16 and 18.

90 The supporting plate is provided with elongated apertures at longitudinal intervals for receiving the upper end portions of the bow-shaped prongs and it will be understood that if the carrier-bar is moved forwardly 95 the prongs will have a corresponding movement, and that the prongs will swing rearwardly when the carrier-bar moves rearwardly.

The forward movement of the prongs is 100 caused by the movement toward each other, of the handles, and during this movement of the handles the prongs will swing forwardly and upwardly to the position of parts shown in Fig. 2, of the drawings, and when by action of the spring 15 the handles move outwardly from each other, the prongs 105 will swing rearwardly and the pressure-bars

will move outwardly from each other, the movements being coincident.

The movements last mentioned for the bow-shaped prongs, is effected by means of a lazy-tongs 21, in conjunction with a pair of cross-levers 22, the latter being pivotally mounted on the pivot pin 14. The rear part of the lazy-tongs is mounted pivotally on the hanger 19.

10 By referring to Fig. 8 of the drawings it will be seen that a movement of the handles toward each other will cause a forward movement of the carrier-plate for the reason that the pin 23 will be moved forwardly, 15 said pin being mounted in the front part of the lazy-tongs and also having a mounting in the front end portion of the carrier frame, said lazy-tongs having a pair of keepers C 20 slidingly mounted in the curved slots D of the lazy-tongs.

Numeral 24 indicates a spring which is provided for the lazy-tongs to cause the carrier plate to move rearwardly when the handles move outwardly from each other.

25 Numeral 25 indicates a slot which is provided in the supporting plate for receiving the pin 23.

It will thus be seen that the movement toward each other, of the pressure-bars and 30 forward swinging movements of the prongs will be simultaneous when the handles are moved toward each other.

The keepers C will also move toward each other in the curved slots D of the lazy-tongs, 35 the result being that the tongs will be extended and the pin will move in the slot 25, its movement being forwardly of the device for moving the carrier-plate forwardly, and since the pivotal mountings of the 40 prongs are between the ends of said prongs, they will swing forwardly, elevating the hair, and since the hair will be elevated at the time it is pressed between the heated bars 12 and 13 it will have the looped form 45 desired.

The casing operates to conserve the heat, also it provides a support for some of the operating parts and is open at its bottom, its lower edges being provided with numerous teeth 26 which, during operation, engage 50 the scalp.

The teeth operate to dispose the prongs in spaced relation relative to the scalp.

The device is disposed transversely, of 55 and upon the hair.

In operation the handles are then moved toward each other, the result being that the prongs will elevate the hair in the form of a loop between the pressure-bars, and said 60 bars will be moved toward each other for heating and pressing the hair.

In Fig. 2 of the drawings, a strand of the hair 27, is shown to illustrate its position between the pressure bars.

65 In this view only a part of the device ap-

pears to be utilized, but it will be understood that, in practice, all of the prongs may engage the hair to form the loops.

Means are provided for maintaining the pressure-bars parallel with each other so 70 that the pressure upon the hair will be practically uniform.

For this purpose each pressure-bar is provided with a pivot-pin 28.

At 22, is indicated a pair of actuating levers disposed in crossed relation and mounted upon the pin 14.

Each lever 22, is pivotally mounted at one of its ends on a pressure-bar and its opposite end is provided with a slot 29, for receiving a pivot pin 28.

Slots 29 are equi-distant from the pivot pin 14 and when the handles are moved toward each other, the pressure-bars will remain parallel relative to each other during 85 all of their movements.

While I have shown and described specific construction for the device I do not limit myself to form, size, proportions or minor details, and changes may be made as found to be of advantage without departing from the spirit of the invention, said changes being within the scope of the invention as claimed.

I claim as my invention.—

1. A hair waver comprising, in combination with a pair of electrically heated pressure-bars movable toward each other for engaging the hair therebetween, of a plurality of curved prongs disposed in a plane between and movable coincidently with said bars for engaging the hair.

2. In a hair waver, the combination with a pair of pressure-bars movable toward each other for engaging the hair, of a plurality of curved prongs mounted in a plane between and movable coincidently and approximately parallel with said bars for engaging the hair.

3. In a hair waver, a casing open at its bottom, a pair of pressure-bars within and arranged to be moved toward each other for engaging the hair, a carrier-plate disposed in the casing approximately parallel with said bars, a plurality of curved prongs 110 pivotally mounted on the carrier-plate, said plate being longitudinally movable coincidently with the movements of said bars for causing swinging movements of said prongs.

4. A hair waver, comprising a pair of pressure-bars movable toward each other for pressing the hair therebetween, and a plurality of curved prongs arranged to swing coincidently with the movements of said bars for engaging the hair.

5. A hair waver, comprising a casing open at its bottom, a pair of pressure-bars within the casing movable toward each other for engaging the hair, and a plurality of prongs

in the casing each having a pivotal mounting and arranged to swing coincidently with the movements of said bars for engaging the hair.

5 6. In a hair waver, a casing open at its bottom, and having its side walls provided with teeth projecting below said walls, a pair of pressure-bars in the casing arranged to be moved toward each other for engaging 10 the hair, and a plurality of curved prongs in the casing mounted to permit swinging movements coincidently with the movements of said bars for engaging the hair.

7. A hair waver, comprising a pair of pressure-bars each provided with a pivot-pin, a pair of actuating levers pivotally connected between their ends each having a pivotal connection at one of its ends with a pressure-bar, its opposite end being provided 20 with a slot for receiving the pivot-pin of a

pressure-bar, the slots in said levers being equi-distant from the pivotal mounting of said levers, and a plurality of curved prongs movable coincidently with said bars for elevating the hair.

8. A hair waver, comprising a casing having an open bottom provided with teeth, a pair of pressure-bars in the casing movable toward each other for engaging the hair, a pair of pivotally connected actuating levers 30 movable by the pressure-bars, a lazy tongs movable by said levers, a carrier-plate movable by the lazy-tongs and a plurality of prongs for engaging the hair, said prongs being movable in planes between the pressure-bars by said carrier-plates, for engaging the hair.

In testimony whereof, I have affixed my signature.

WILLIAM M. NEVOTTI.
